(57) **CLAIM**

The ornamental design for a throat bush as shown and described.

DESCRIPTION

FIG. 1 is a first end view of the throat bush showing our new design;

FIG. 2 is a second opposing end view thereof;

FIG. 3 is a perspective view from the first end thereof;

FIG. 4 is perspective view from the second opposition end thereof;

FIG. 5 is a side view thereof; and,

FIG. 6 is cross-sectional side view thereof.

The broken lines in the drawings depict structure that makes up no part of the claimed design.
